TUNING INDICATOR CIRCUITS

Rudolph H. Siemens, Richmond Hill, N. Y., assignor, by mesne assignments, to Radio Corporation of America, New York, N. Y., a corporation of Delaware

Application August 26, 1936, Serial No. 98,006

6 Claims. (Cl. 250—20)

My invention relates to circuits for converting high frequency alternating currents into low frequency and direct currents, and more particularly to radio circuits incorporating visual voltage or tuning indicators of the electron discharge type.

One embodiment of such a device useful as a tuning indicator and described in Patent 2,051,189 allowed August 18, 1936 to Herbert M. Wagner and assigned to the Radio Corporation of America, comprises an envelope having within it a straight thermionic equipotential cathode provided with two separate emitting sections, one of which is surrounded by amplifier elements which 5 may comprise a control grid and anode, and the other of which is surrounded by the tuning indicator elements of the tube consisting of a straight control electrode parallel to the cathode and an anode or target coated with fluorescent material which may be concentric with and 10 surrounding the cathode and the control electrode. In operation electrons flow from the cathode to the fluorescent anode with sufficient velocity to bombard the fluorescent anode and render it luminous. The control electrode is connected to the 15 amplifier anode and the tube so connected into a radio receiving circuit that when the circuit is tuned to resonance with an incoming signal the luminous portion of the plate is of a pre-determined width. The device is to advantage so 20 connected that when the circuit is tuned to resonance the luminous portion of the anode of the tuning indicator portion is of maximum width and the dark portion of minimum width, preferably the entire anode becoming fluorescent and 25 the dark portion disappearing.

In one of the conventional circuits in which the above tuning indicator tube is used, the intermediate or radio frequency amplifier of the radio receiver is coupled to a thermionic diode rectifier having in its output a resistor across which a direct voltage is developed and which is applied as a grid bias voltage to the intermediate frequency or radio frequency amplifier to obtain 30 an automatic volume control action, and also to the audio amplifier. The grid of the tuning indicator above described may also be connected to the same point in the output of the rectifier, and the indicator responds to this bias voltage to visually indicate the amplitude of the rectified voltages impressed on the rectifier by the preceding amplifier stages. Maximum voltage is indicated 35 when the receiving circuit is tuned to resonance. In some cases a separate rectifier is used solely 40 for the purpose of providing a direct voltage bias

for the tuning indicator tube. In either case it is necessary to employ a stage of rectification before the tuning indicator.

It is the object of my invention to provide a circuit arrangement making use of the above described tuning indicator tube as a combined visual tuning or voltage indicator, detector or rectifier and automatic volume control device. 5

The novel features which I believe to be characteristic of my invention are set forth with particularity in the appended claims, but the invention itself will best be understood by reference to the following description taken in connection with the accompanying drawing in which the single figure of the drawing is a diagrammatic representation of a radio receiving circuit embodying 10 my invention.

Briefly the signal received is fed to an amplifier which is coupled to the combined tuning indicator, detector or rectifier and automatic volume control device by connecting in accordance with my invention the output of the amplifier between the grid and cathode of the tuning indicator tube. Rectification is accomplished by these 15 two electrodes. The output of the tuning indicator tube is coupled to the amplifier to control its gain and to the audio frequency amplifier, proper filtering arrangements being used. By suitable 20 circuit arrangement the indicator tube develops its own bias which is applied to the grid to cause 25 indication of the amplitude of the rectified voltage and hence resonance conditions and filtering arrangements are also provided to insure 30 proper operation of the tuning indicator portion 35 of the tube.

Referring to the drawing, the signal received by the antenna 10 is impressed on the amplifier 11, the output of which is coupled to the tuning indicator tube by means of a tuned circuit comprising 40 the secondary of the transformer 12 and the condenser 13.

The thermionic voltage or tuning indicator has an envelope 14 containing a two-section cathode 15, the amplifier portion of the tube comprising grid 17 and anode 18 surrounding one section of 45 the cathode and the visual indicating portion surrounding the other portion of the cathode and comprising an anode 19 which fluoresces during operation, and a control electrode 20 electrically connected to the anode 18 for determining the 50 portion of the fluorescent anode upon which the electrons from the cathode strike to cause it to fluoresce, the shadow caused by the control rod on the anode depending upon the difference in 55 voltage between the control electrode 20 and the

anode 19. Resistor 21 is connected between the anode 18 and the anode 19 for developing a difference in potential between the anode 19 and electrode 20 during operation of the tube when current flows in the anode of the tube.

In accordance with my invention the tuned circuit comprising the secondary of transformer 12 and condenser 13 is connected between cathode 15 and grid 17 of the indicator tube 14, resistor 22 and condenser 23 being connected in series with the tuned circuit and the indicator tube. Rectified voltage comprising an audio frequency component and a more or less steady direct voltage component appears across the impedance in the form of a resistor 22, one side of which is connected to cathode 15 and ground, and the other side of which is connected to one side of the tuned circuit, and the by-passing condenser 23 connected in parallel across resistor 22. The side of resistor 22 connected to the tuned circuit becomes negative with respect to ground and cathode when the alternating voltages impressed on the rectifier circuit by amplifier 11 are rectified, the condenser 23 being charged to peak rectified voltages which appear across the resistor 22. Rectification and detection therefore takes place between grid 17 and cathode 15 of indicator tube 14.

This bias voltage appearing at the tuned circuit end of resistor 22 is applied to the amplifier 11 to control its gain through the filter comprising resistor 24 and condenser 25, which filters out the audio frequency voltages appearing across resistor 22. The audio frequency voltages are applied through a coupling condenser 26 to audio frequency amplifier 27, the output of which is connected to a translating device such as loud-speaker 28. The voltage drop across resistor 22 is also applied to the grid 17 of the tube 14 and thus makes the tube self biasing. This action is made use of in the indicator portion of the tube as will be described below.

In operation the signals received by antenna 10 are amplified and impressed upon the tuned circuit comprising secondary of transformer 12 and condenser 13, rectification taking place between the grid 17 and cathode 15, the direct voltage and audio voltage appearing across resistor 22 and condenser 23 and used for automatic volume control and to excite the audio amplifier, as above described. The bias developed across this resistor is applied to grid 17 so that the visual indicating tube acts as a self biased device. The degree of bias developed across resistor 22 and hence on the grid 17 determines the current flowing to the anode 18 and hence the drop through resistor 21. With the set detuned very little or no voltage drop appears across resistor 22. Under these conditions cathode 15 and grid 17 are at substantially the same potential so that current flows through resistor 21 to anode 18. Under these conditions anode 18 and control electrode 20 are at a lower potential than the fluorescent anode 19 so that a large shadow is cast on the anode 19, the fluorescent portion of the anode being a minimum. When the set is tuned to resonance to an incoming signal rectified current flows through resistor 22 developing a voltage drop across resistor 22. This appears as a negative bias on the grid 17 and reduces the current flowing in the anode 18 and hence the drop through resistor 21. The potential difference therefore between the control electrode 20 connected to anode 18 and the fluorescent anode is reduced permitting more of the fluorescent anode to be struck by electrons from the

cathode 15 to cause the anode to fluoresce. The constants of the circuit can be so chosen that substantially the entire anode fluoresces when the set is tuned to resonance. Inasmuch as the audio frequency voltage appears across resistor 22 and hence on grid 17, if this voltage is not bypassed and is permitted to appear across resistor 21 the result would be a fluctuation of the pattern on the fluorescent anode. Therefore, the condenser 29 is provided between cathode 15 and anode 18 to by-pass these voltages back to the cathode so that only a steady voltage drop appears across resistor 21.

It will thus be seen that by the novel circuit which I have provided I eliminate the need for a separate diode rectifier and provide a self-biased visual tuning indicator device which also provides rectification for the automatic volume control bias and detection for the audio frequency amplifier, the tube also visually indicating the amplitude of the rectified radio frequency or intermediate frequency voltages as the set is tuned to resonance.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. A circuit for rectifying alternating currents and visually indicating the amplitude of the rectified currents and resulting voltages and including a thermionic device having a cathode, a grid and anode surrounding one portion of the cathode and a fluorescent anode and control electrode adjacent another portion of the cathode, said control electrode being electrically connected to the first anode, means for impressing alternating voltages upon said thermionic device, said means including a circuit connected between the grid and cathode of said thermionic device for rectifying alternating currents and producing rectified voltages and a condenser connected between the first anode and cathode of said thermionic device.

2. A circuit for rectifying alternating currents and visually indicating the amplitude of the rectified currents and resulting voltages, and including a thermionic device having a cathode, a grid and anode surrounding a portion of the cathode, and a fluorescent anode and control electrode adjacent another portion of the cathode, said control electrode being connected to the first anode, an amplifier upon which is impressed an alternating voltage, an output for said amplifier and means for coupling the output of said amplifier to said thermionic device, and including a circuit having an impedance therein and connected between the grid and cathode of said thermionic device for rectifying amplified alternating currents and producing rectified voltages, said rectified voltages appearing across said impedance, and a condenser connected between the first anode and said cathode.

3. A circuit for rectifying alternating currents and visually indicating the amplitude of the rectified currents and resulting voltages, and including a thermionic device having a cathode, a grid and anode surrounding a portion of the cathode,

- and a fluorescent anode and control electrode adjacent another portion of the cathode, said control electrode being connected to the first anode, an amplifier upon which is impressed an alternating voltage, an output for said amplifier and means for coupling the output of said amplifier to said thermionic device, and including a circuit having an impedance therein and connected between the grid and cathode of said thermionic device for rectifying amplified alternating currents and producing rectified voltages, said rectified voltages appearing across said impedance, a condenser connected between the first anode and said cathode and a resistor connected between the first anode and said fluorescent anode.
4. A circuit for amplifying and rectifying alternating currents and visually indicating the amplitude of the rectified currents and resulting voltages, and including a thermionic device having a cathode, a grid and anode surrounding a portion of the cathode, and a fluorescent anode and a control electrode adjacent another portion of the cathode, said control electrode being connected to the first anode, an amplifier upon which is impressed an alternating voltage, an output for said amplifier and means for coupling the output of said amplifier to said thermionic device, and including a circuit having a resistor therein and connected between the grid and cathode of said thermionic device for rectifying the amplified alternating currents and providing rectified voltages, said rectified voltages appearing across said resistor, a condenser connected between the first anode and said cathode and a resistor connected between the first anode and said fluorescent anode, and means connected to the first resistor and the amplifier for controlling the gain in said amplifier.
5. A radio circuit for a combined visual tuning indicator, detector and automatic volume control device and including an amplifier upon which radio frequency voltages are impressed and an electron discharge device including a cathode and a grid and anode surrounding a portion of the cathode and a visual tuning indicating section comprising a fluorescent anode surrounding another portion of said cathode and a control electrode positioned between said fluorescent anode and the cathode and connected to the first anode, a circuit connected between said grid and cathode and coupled to said amplifier for rectifying the voltages impressed on said amplifier and a resistor in said circuit across which the rectified voltages appear, and a connection between said resistor and said amplifier for controlling the gain of said amplifier, and a condenser connected between the anode and cathode of said electron discharge device.
6. A radio circuit for a combined visual tuning indicator, detector and an automatic volume control device including an amplifier upon which radio frequency voltages are impressed, an electron discharge device comprising a cathode, a grid and an anode surrounding one portion of said cathode and a fluorescent anode adjacent another portion of the cathode, a control electrode between said fluorescent anode and said cathode and electrically connected to the first anode and a resistor connected between the first anode and the fluorescent anode, and a circuit including a resistor connected between the grid and cathode of said electron discharge device for rectifying the amplified voltages from said amplifier, said rectified voltages appearing across said resistor, a connection between said resistor and said amplifier for controlling the gain of said amplifier, an audio frequency amplifier and means for coupling said audio frequency amplifier to the circuit connected between the grid and cathode of said electron discharge device and a condenser connected between the first anode and cathode of said electron discharge device.
